MOTOR STARTING AND CONTROL MECHANISM

Filed Nov. 7, 1928

UNITED STATES PATENT OFFICE

HAROLD A. MAXFIELD, OF WORCESTER, MASSACHUSETTS

MOTOR STARTING AND CONTROL MECHANISM

Application filed November 7, 1928. Serial No. 317,803.

This invention relates to starting and control mechanism for direct current motors, particularly where such motors are frequently started and stopped under heavy load conditions.

It is the object of my invention to simplify the control mechanism, to reduce the current and heat losses, and to secure greater service from a given size of motor.

10 With this general object in view, my invention relates in part to the provision of an improved and novel current control device in a direct current motor.

In the preferred form, an inductive resistance is placed in parallel with the non-inductive resistance heretofore commonly used.

15 My invention further relates to arrangements and combinations of parts which will be hereinafter described and more particularly pointed out in the appended claims.

Preferred applications of my invention are shown in the drawings in which

20 Fig. 1 is a diagrammatic view showing my improvements applied to a direct current series motor;

Fig. 2 is a time-current chart, illustrating the operation of my invention;

25 Fig. 3 shows my improvements applied to a shunt type of direct current motor;

Fig. 4 is a diagrammatic view indicating a slight modification; and

Fig. 5 is a diagrammatic view of a further modification.

30 Referring to Fig. 1, I have shown a series-type, direct current motor having an armature A, a series field coil F, a starting resistance R, a so-called "plugging" resistance R', and a main switch or contactor 10, these parts being of a more or less usual construction.

I have also provided an inductive resistance 12, mounted in series with an additional non-inductive resistance 13, these resistances 45 12 and 13 being mounted in parallel with the starting resistance R previously described. The inductive resistance 12 may have either an air core or an iron core.

The contactor 14 is provided for short-circuiting the resistance R', and a contactor 15

for short-circuiting the parallel resistances 12 and 13.

The resistance R' may be omitted if the motor is not to be reversed or if it is to be reversed by means other than that commonly 55 termed "plugging".

The operation of my improved starting mechanism is as follows, reference being made to Fig. 2:-

It is assumed that the switches or contactors 14 and 15 are open and that the main switch 10 is closed at the point 20, immediately followed by the closing of the contactor 14 at the point 21, which cuts out the plugging resistance R'. As soon as the switch 14 is 60 closed, the current will rise to the value indicated by the point 22, at which point the starting torque is a maximum and the speed of rotation is a minimum. At this point the flow of current through the field coil F and 65 armature A is controlled by the parallel resistances R and 12 and 13.

In the circuit through the resistances 12 and 13 very little current flows at this time because of the transient current action of this 70 inductive circuit, presenting great obstruction to the flow of current while the magnetic field of the inductive resistance 12 is increasing.

As the armature picks up speed, a counter 80 electro-motive force is developed which gradually reduces the current value to the point 23 to Fig. 2. During this gradual lowering of the current value, however, the inductive resistance 12 becomes more fully stored with 85 magnetic energy and presents less and less obstruction to the flow of current.

The resistance 12 therefore has the effect of gradually cutting itself out and an increasing amount of current is allowed to flow 90 through the resistances 12 and 13. This modifies the reduction in current flow, as indicated in Fig. 2, and causes the point 23 to be spaced at a greater time interval from the point 21.

When the current finally drops to the value indicated at 23, an automatic device closes the switch 15, cutting out the resistances R and 12 and 13 entirely, and the current flow 95 immediately increases, as indicated at the 100

point 24. As the motor thereafter picks up more speed, the current falls according to the normal characteristic of the motor, as indicated by the curve 25.

5 A common form of automatic device for closing the switch 15 is indicated in Fig. 1 and comprises a solenoid plunger 30 for the switch 15, a solenoid plunger 32 pivotally connected to a lever 33 and supporting a 10 weight W and also a plurality of solenoid coils A, B and C. When the motor is at rest the coils A, B and C are deenergized and the weight W holds the switch 15 open. As the motor starts up, the current through the coil 15 A increases to a point where the weight W is lifted and the lever 33 swings downward away from the plunger 30. By this time, however, the solenoid coil B is energized sufficiently to hold the plunger 30 raised and 20 the switch 15 opened. When the current drops, however, to the point 23 (Fig. 2) the weight of the plunger 30 overcomes the coil B and the switch 15 closes. As soon as the switch closes the coil C is energized and this 25 coil is arranged to act in the opposite direction from the coil B and to thereafter hold the switch 15 closed even when the current in the coil B increases as indicated at 24.

This automatic device is of the usual construction and the details thereof form no part of my present invention.

In Fig. 1 I have indicated a certain amount of non-inductive resistance 13 in series with the inductive resistance 12, but under certain conditions the shunt or parallel resistance may be entirely inductive, as indicated at 30 in Fig. 4.

For a compound motor, the operation will be substantially the same as for a series motor, a shunt coil 32 being connected as indicated in Fig. 1 entirely around the armature, the series field, and the control mechanism above described.

The arrangement for a shunt motor is indicated in Fig. 3, with the shunt coil 40 connected around the armature and starting mechanism, and with the control mechanism inserted in series with the brushes.

In Fig. 5, I have shown an inductive resistance 31 in series with the motor, which is of value in producing a slow-starting or "cushion" effect, when used in combination with my control mechanism involving the resistances R, 12 and 13. The resistance R' 55 may be either used or omitted in this combination.

Having described the construction and operation of my improved starting and control mechanism, I will further explain the 60 advantages thereof.

In the first place, the single switch or contactor 15 takes the place of two or more similar switches which have been heretofore found necessary until my inductive resistance 12 was used, it being necessary to cut

out the resistance R in sections, reducing the resistance as soon as the current dropped to a predetermined level, which occurred much more promptly when a simple non-inductive resistance was used.

With my improved construction, the inductive resistance 12 acts in effect to cut itself out as it becomes stored with energy, thus reducing the number of automatic cut-outs to a minimum. Furthermore, it will be noted that the inductive resistance 12 economizes current, as it acts to store up energy and feed it back into the system rather than converting the electricity into the form of heat which passes out of the system, as is the case with the usual non-inductive resistance.

The action of this new control device may be secured by proper design so that the same starting performance of the motor may be obtained with less loss in the motor. This end may be gained by decreasing the value of current at 22 and 24 (Fig. 2) and increasing the value of current at 23. This reduces the temperature rise in the motor and it is frequently found that a smaller size motor will perform the same duty without over-heating that required a larger motor under the old control methods, unless a large number of automatic cut-out devices are employed, which scheme is prohibitive in cost and impractical beyond a certain point.

If it is particularly desired to speed up the operation of the motor rather than to reduce the size, a resistance may be so designed that the point 23 will be reached more promptly and the starting period will be reduced, this operation being commonly accomplished, however by a greater heat loss.

Having thus described my invention and the advantages thereof, I do not wish to be limited to the details herein disclosed otherwise than as set forth in the claims, but what I claim is:—

1. A direct current circuit comprising a motor having an armature, a non-inductive resistance in series therewith, an inductive resistance in series with said armature but in parallel with said non-inductive resistance, and means to short circuit said parallel resistances on the occurrence of a predetermined drop in armature current.

2. A direct current circuit comprising a motor having an armature, a field coil in series therewith, a non-inductive resistance in series with said armature and said entire field coil, and an inductive resistance also in series with said armature and said entire field coil but in parallel with said non-inductive resistance.

3. A direct current circuit comprising a motor having an armature, a non-inductive resistance in series therewith, and an inductive resistance and a non-inductive resistance in series with each other and collective-

ly in parallel to said first-mentioned resistances.

4. A direct current circuit comprising a motor having an armature, a non-inductive resistance in series therewith, an inductive resistance and a non-inductive resistance in series with each other and collectively in parallel to said first-mentioned resistance, and means to short-circuit said parallel resistances.

10 In testimony whereof I have hereunto affixed my signature.

HAROLD A. MAXFIELD.
